UNITED STATES PATENT OFFICE.

OSCAR P. NYSTROM, OF HOLLAND, MICHIGAN, ASSIGNOR TO HOLLAND FURNACE COMPANY, OF HOLLAND, MICHIGAN, A CORPORATION OF MICHIGAN.

FURNACE HUMIDIFIER.

Application filed February 24, 1925. Serial No. 11,082.

To all whom it may concern:

Be it known that I, OSCAR P. NYSTROM, a citizen of the United States of America, residing at Holland, in the county of Ottawa and State of Michigan, have invented certain new and useful Improvements in Furnace Humidifiers; and I do hereby declare the following to be a full, clear, and exact description of the invention, such as will 10 enable others skilled in the art to which it appertains to make and use the same.

This invention relates to humidifiers for use in furnaces, wherein water may be evaporated in the air heating space enclosed between the outer casing and the fire pot, combustion chamber and radiator of the furnace. It has been a general practice heretofore to locate water pans, holding a considerable quantity of water, in this space, usually directly in front of the fire pot so that heat therefrom applied to the water caused its evaporation. Inasmuch as the surface area of the water in the water pan is limited, the amount of evaporation is much less than it should be for the proper humidifying of the air passing from the furnace to the rooms which it heats. Moreover, these water pans must be filled periodically and in practice the user of the furnace may or may not keep the water pan filled, usually the latter. This results in the air going to the rooms heated by the furnace being very dry.

In the present invention it is designed that a humidifier shall be provided in which a very large evaporation surface is furnished and in which the humidifier is at all times supplied with a continuous supply of water so that it never becomes dry. This is one of the primary objects of the invention. A further object of the invention is to locate the humidifier at the extreme lower portion of the air heating space between the enclosing casing and the fire pot and to make the humidifier in such way that it occupies very little, in fact, for practical purposes, no space in such enclosed heating space and in no way interferes with the air circulation. A still further and very important object of the invention is to provide a drain for excess of water which may be supplied to the humidifier over and above what is evaporated, such excess being carried and delivered to the ash pit where it is absorbed by the ashes. This eliminates dust from the ashes and at the same time supplies moisture to the air

going to the burning fuel, resulting in better combustion of the fuel and, even if all of the moisture supplied to the ashes should be evaporated, the dust is settled by reason of the fact that ashes once saturated with water and thereafter dried are not dusty, the dust having been eliminated because of the previous saturation of the ashes with water. And a still further, and from an economical standpoint, very important object and purpose of this invention is to construct the water holding parts of the humidifier as an integral portion of the ash pit casting there being substantially no increase in the cost of manufacture of the casting, while with the elimination of the water pan its cost is eliminated.

The construction by means of which these results and others not at present specifically stated are attained is shown in the accompanying drawing, in which,

Fig. 1 is a fragmentary central vertical section from front to rear through the lower part of a furnace equipped with my invention.

Fig. 2 is a horizontal section taken substantially on the plane of line 2—2 of Fig. 1, and

Fig. 3 is a fragmentary enlarged elevation illustrating the means of controlling the water supply to the humidifier.

Like reference characters refer to like parts in the different figures of the drawing.

In the construction of the furnace below the fire pot 1, which is of substantially circular outline, an ash pit 2 is located, it having a curved form at its rear portion corresponding to the form of the fire pot which rests thereon. Each side of the ash pit adjacent its front portion is extended forward in a side 3, the two sides 3 being parallel to each other and integrally connected at their upper edges by a cross top plate 4 which, in practice, is inclined downwardly and inwardly at a slight angle to the horizontal. The ash pit is open at the front and the usual cast plate 5, on which the fire and ash pit doors are mounted, is located in front of the ash pit, the door 6 to the ash pit being shown as it is regularly constructed. In the bottom of the fire pot a grate 7 is mounted through which the ashes 8 pass to the ash pit as shown.

The construction thus far outlined is old and well known. It has been the practice

heretofore to place the water pan above the top 4 over the forward extension to the ash pit and between the fire pot and the front of the furnace casing. With this invention the 5 water pan is eliminated. In place thereof upwardly extending shallow ribs or sides 9 are cast integral with the part 4, being connected at their front ends by an integral front rib 10 and at their rear ends by a 10 similar rib 11 which is spaced a short distance from the fire pot casting. An opening 12 is made through the part 4 a distance in front of the rib 11, and a groove 13 is formed in the under side of the part 4 extending 15 downwardly and inwardly to a point substantially directly under the rib 11.

It is designed that water shall be continuously supplied to the shallow container which is thus made having the bottom 4, 20 sides 9 and outer and inner cross connecting ribs 10 and 11. The water may be supplied from any suitable source of supply through a pipe 14, at the end of which a manually operable control valve 15 is mounted for 25 regulating the amount or quantity of water which is passed to the humidifier. Any suitable means may be used to carry the water to the humidifier. One means is shown consisting of a horizontal pipe 16 which extends 30 across the outer part of the humidifier above the bottom 4 thereof, having an end portion extending outwardly through the front casting 5 and being equipped at its outer end with a union 16^a open to receive water 35 delivered through the valve 15 from the pipe 14. It is desirable that the flow of water to the pipe 16 may be observed that the amount of flow can be better regulated. The pipe 16 in its under side may be provided 40 with a number of small openings in its length, the water passing therethrough at different points in the length of the pipe and dropping to the bottom 4 of the humidifier.

45 This water when delivered to the humidifier spreads over the bottom 4 and has a tendency to flow downwardly by gravity toward the lower inner portion of the humidifier. The heat from the fire pot is directed against the bottom 4 of the humidifier and the water passing thereover so that the water is quickly evaporated and mingles with the heated air which is rising all of the 50 time between the outer casing 19 of the furnace and the inner heat radiating parts of the furnace. In fact while the furnace is operating during the daytime to heat the rooms to the required temperature all of the 55 water which is delivered is evaporated but at night when the furnace is closed the evaporation of the water is not so great and in time a quantity thereof indicated at 17 collects at the lower part of the humidifier in front of the inner rib 11. When it has 60 reached a level such that the over-flow open-

ing 12 is reached, the excess water not evaporated passes through said opening and thence down guide groove 13 dropping, as indicated at 18, into the ashes 8 contained in the ash pit.

70 The humidifier construction described is very economical to produce requiring only the addition of the enclosing ribs 9, 10 and 11 on the part 4 of the ash pit casting, all of which can be made when the ash pit casting is molded without additional expense except for the very little more material that is needed. The pipes 16 and 14 with the valve 15 or any other equivalent construction which may be used are inexpensive and their 75 cost is balanced by the cost of the water pan which is eliminated with this humidifier. A large supply of water and a large water pan to contain the same are eliminated, the removal of the water pan removing what has been heretofore an obstruction to the free circulation of the heated air in the hot air space enclosed by the outer casing of the furnace. It is evident that the front side 80 of the furnace fire pot many times becomes very hot and the water pan has stood in the way of proper radiation of heat therefrom. The part 4, constituting the bottom of the humidifier and the top of the forward extension to the ash pit, is directly in line for 85 heat radiated from the front side of the fire pot and water dropping by drops onto this plate is quickly raised to vaporizing temperature and diffused into the heated air 90 going from the furnace. The consumption 95 of a considerable quantity of heat in a large body of water such as is required in water pans is obviated.

100 While the invention has been described and shown as forming an integral part of the ash pit casting it is evident that with furnaces already installed and in use that it is quite possible and practical to make a 105 separate similar humidifier unit which may be placed upon the part 4 of the ash pit casting, this without departing in any way from the invention. With this construction of humidifier not only is a very large 110 evaporating surface for water provided and evaporation of the water made correspondingly rapid, but there is also a hot plate 115 evaporation provided, drops of water falling on the hot plate with consequent almost instant evaporation. As a rule the amount of 120 moisture supplied with warm air furnaces, even where the water pan is kept filled with water at all times, is much too small, but with this invention the moisture supplied to the heated air going to the rooms of a house 125 heated by the furnace is greatly increased. The supply of water to the humidifier is continuous and there is no likelihood of the 130 humidifier at any time being dry; and the excess of water, supplied to the humidifier at the times when the furnace is not operat-

ing at full capacity, overflows and is carried to the ash pit saturating the ashes with all of the resultant advantages coming therefrom. The invention is very simple, very

5 practical and very efficient in every respect. It is defined in the appended claims and is to be considered as comprehensive of all forms of structure coming within the scope of said claims.

10 I claim:

1. In a furnace, an ash pit casting and a fire pot casting located above the ash pit casting, said ash pit casting at one side having outwardly extending spaced apart 15 sides and a top disposed between the upper edges of the sides, means for continuously supplying water to and against the upper side of said top, and means cast integral with the top and extending upwardly therefrom preventing flow of the water beyond either side edge of the top or against the fire pot casting, substantially as and for the purposes described.

2. In a furnace, an ash pit casting and a 25 fire pot casting located above the ash pit casting, said ash pit casting at one side having outwardly extending spaced apart sides and a top disposed between the upper edges of the sides, said top being provided 30 with means whereby a limited quantity of water may be held thereon, and means for continuously supplying water to said top, substantially as described.

3. In a furnace, an ash pit casting and a 35 fire pot casting located above the ash pit casting, said ash pit casting at one side having outwardly extending spaced apart sides and a top disposed between the upper edges of the sides, vertical ribs extending 40 upwardly short distances from said top adjacent each side edge thereof, an inner cross rib connecting the inner ends of the vertical ribs integral therewith and with said top, an outer cross rib connecting the outer ends 45 of said side ribs integral therewith and with said top, and means for supplying water continuously to said top within the space surrounded by said ribs, substantially as described.

50 4. In a furnace, an ash pit casting and a fire pot casting located above the ash pit casting, said ash pit casting at one side having outwardly extending spaced apart sides and a top disposed between the upper 55 edges of the sides, said top being inclined downwardly and inwardly at an angle to the horizontal, side ribs integral with and extending upwardly from the top adjacent each side edge thereof, and a cross rib integral with the top and the side ribs connecting the inner ends of said cross ribs and located adjacent but spaced from the fire pot, substantially as described.

5. A construction containing the elements 65 in combination defined in claim 4, said top

at a distance back of the cross rib having a drainage opening therethrough, substantially as described.

6. A construction containing the elements in combination defined in claim 4, said top 70 a distance in front of the cross rib having a drainage opening therethrough and having a groove at its under side extending from said opening downwardly and inwardly, substantially as described. 75

7. In a furnace including an ash pit and fire pot, said fire pot being located above the ash pit, a water receiving receptacle located in front of the fire pot and above the ash pit, means for continuously supplying a 80 predetermined amount of water to said water holding receptacle, said receptacle having a drain opening for excess of water, and means for conducting the excess of water to the ash pit, substantially as described. 85

8. In a furnace, a water holding receptacle for receiving water located above the ash pit and adjacent the fire pot of the furnace, means for continuously supplying a 90 predetermined amount of water to said receptacle, and means for draining excess water from the receptacle to the ash pit below the fire pot.

9. In a furnace including an ash pit and a fire pot located above the ash pit, said ash pit having an outwardly extending portion at one side thereof, a receptacle located at the upper side of said projecting portion of the ash pit adapted to contain water, said 100 receptacle having a varying depth and formed with a drainage opening at a point above the lowermost portions of the receptacle whereby only a predetermined amount of water can be held in the receptacle, any 105 excess draining therefrom through the drainage opening and into the ash pit, and means for continuously supplying water to said receptacle. 110

10. In a furnace, an ash pit casting, a fire 110 pot casting located above the fire ash pit casting, said ash pit casting at one side having an outwardly extending portion comprising sides and a top connecting the upper edges of said sides, said top having portions located in a lower plane than the remaining portions thereof, whereby water delivered to the upper side of said top will normally flow to said lower portions, and a drainage opening through said top located 115 at a point above the lowermost portions of the top whereby only a predetermined quantity of water can be held in said top, excess passing through said drainage opening to the ash pit, substantially as described. 120

11. In a furnace, an ash pit casting and a fire pot casting located above the ash pit casting, said ash pit casting at one side having an outwardly extending portion comprising vertical sides and a top integrally 130

connecting the upper edges of said vertical sides, said top having a drainage opening therethrough, means located on said top in front of the fire pot casting to which water 5 may be delivered and a predetermined quantity thereof held, any excess over said predetermined quantity passing through said drainage opening to the ash pit, and means for continuously supplying water to said 10 water holding means, substantially as described.

12. In a furnace, an ash pit casting formed with an outwardly extending portion at one

side thereof comprising spaced apart sides and a top integrally connecting the upper 15 edges of said sides, means for continuously supplying a limited quantity of water to said top, a fire pot casting located above the ash pit casting adapted to radiate heat therefrom to the top of the ash pit casting or to 20 water thereon, and means for confining the water to a prescribed area on the upper side of said top, substantially as described.

In testimony whereof I affix my signature.

OSCAR P. NYSTROM.
